GARDEN HOSE VALVE

Elmer A. Fuglie, Winona, Minn., assignor to Winona
Tool Manufacturing Company, a partnership

Application August 17, 1953, Serial No. 26,492

Term of patent 14 years

(Cl. D91—3)

Fig. 1

Fig. 2

Fig. 3

Fig. 4

Fig. 5

Fig. 1 is a top plan view of a garden hose valve embodying my new design;

Fig. 2 is a side elevation of the valve shown in Fig. 1;

Fig. 3 is a bottom plan view of the valve;

Fig. 4 is an end elevation of the valve shown in Figs.

1 and 2 as seen from the left side of those figures; and

Fig. 5 is an end elevation of the valve as seen from the left hand side of Figs. 1 and 2.

I claim:

The ornamental design for a garden hose valve, as shown.
